FISHING TACKLE BOX

Raymond J. Sierzega, 17220 S. Wausau,
South Holland, Ill. 60473

Filed Dec. 26, 1968, Ser. No. 15,114

Term of patent 14 years

Int. Cl. D3—99

U.S. Cl. D87—1

FIG. 1 is a left side, top and front perspective view of a fishing tackle box, showing one form of my new design;

FIG. 2 is a left side elevational view of the form shown in FIG. 1, the opposite side being substantially a mirror image thereof;

FIG. 3 is a left side elevational view of a fishing tackle box showing a second form of my new design;

FIG. 4 is a left side elevational view of a fishing tackle box showing a third form of my new design.

The characteristic features of the design reside, in a fishing tackle box of the type disclosed, in the watershed type overlapping arrangement of the front faces of the drawers, as shown.

I claim:

The ornamental design for a fishing tackle box, as shown and described.
